UNITED STATES PATENT OFFICE

GUY F. KOTRBATY, OF NEW YORK, N. Y.

RAIL

Application filed July 27, 1928. Serial No. 295,706.

This invention relates to an improved rail, and more particularly to a combination rail having a removable or replaceable tread.

Hitherto, railroad rails in use on sections 5 of heavy traffic have been subject to excessive wear at the tread portion due to the increasing weight of train equipment, which is now standard practice throughout the country. The greatest wear is experienced by subway 10 lines in the populous cities of the country, notable examples of which are those of New York and Boston. In both of these cities, the subway lines are very tortuous, the result being that the replacement costs for rails used 15 at the numerous curves is excessive due to the frequency of such replacements. A classic example of such practice is that afforded by the Interborough Rapid Transit Company of New York City at its City Hall Station. The average life of rails used in this 20 particular section of this subway is not over three months, due to the extremely sharp curves in the loop, at the station.

An analysis of the failures of rails under 25 conditions of use reveals the fact that substantially the entire wear of the rail occurs at the top or tread portion. Various attempts have been made in the past to remedy this situation by providing rails with removable 30 treads. These attempts have not been successful due to a variety of causes, the chief one being that with increase of tonnage of rolling stock, the design of such prior art replaceable treads has not permitted their use, 35 the treads not having sufficient mechanical support to enable them to be retained in position when subjected to the enormous stresses above noted. A further difficulty which is 40 frequently encountered is the attrition or wearing down of the ends of the rails due to the hammering action of the wheels as the rolling stock moves over the ends of the rails.

45 Improvements in road beds, and welding together or bonding of the rail ends have not mitigated this trouble to any appreciable extent, and it is common knowledge that the rail equipment of many railroads and street railways is in poor shape due to the condi-

tion of the rail ends, which condition is constantly aggravated by continued use.

It is an object of the present invention to provide an improved rail which includes a replaceable tread, the whole being so constituted and arranged as to provide a wearing surface of maximum resistance to attrition stresses, while being adapted to be readily replaced without disturbing the rail proper or its embedment. 55

It is a further object of this invention to provide such an improved combination rail with a replaceable tread which may be made of wear resistant metal. 60

Yet another object of this invention is the provision of an improved rail with a replaceable tread, the whole being so designed and constituted as to provide a continuous metallic base for the tread portions, thereby eliminating attrition of the rail tread ends due 65 to the pounding of the rolling stock in passing thereover. 70

These and other desirable objects will be described in the accompanying specification and illustrated in the drawings, a preferred embodiment being shown by way of example only, for since the underlying principles may be incorporated in other specific mechanical devices, it is not desired to limit this invention thereto, except as such limitations are 75 clearly imposed by the appended claims. 80

In the drawings, like numerals refer to similar parts throughout the several views, of which

Fig. 1 is a cross-section of an improved 85 rail embodying a replaceable tread;

Fig. 2 is a longitudinal front view of a section of a rail;

Fig. 3 is a perspective view of the web member of the combination rail, showing the 90 recessed section for preventing longitudinal displacement of the rail tread;

Fig. 4 is a view similar to Fig. 3 showing a rail tread with an integral locking lug adapted to cooperate with the recessed portion of 95 the web member;

Fig. 5 is a top plan view of a curved section of a rail installation, the treads being shown staggered with respect to the web portions; and 100

Fig. 6 is a view, partly in section and partly in elevation of a plurality of improved rails assembled with the tread ends overlapping the web portions of the rails.

Referring now to the drawings, there is shown in Fig. 1 an improved rail comprising a flanged base 1 and a web portion 2. This web is somewhat thicker than the ordinary web used on standard rails, for a reason which will appear more in detail hereinafter. At its upper portion the web is flared outwardly at 3 and 4 to provide a proper bearing for the tread, designated generally by the numeral 5.

Section 3 of the web is provided at its upper portion with a flat bearing surface 6 which extends the whole length of the rail and inwardly of the web merges with the curved bearing surface 7 of the web extension 8 which, as shown, is a continuation of section 4. Bearing surface 7 forms a groove and is continued at 9 to form a tongue portion which is provided with a flat bearing surface 10 defining the upper limit of section 8 of the web.

Tread member 5 comprises a tread 11 terminating in curved end portions or edges 12, 13. The sides of the member 5 are extended downwardly at 14 and 15 and terminate at bearing surfaces 16 and 17, respectively, which abut bearing surfaces 6 and 10 of the web. The bearing surfaces of the tread member are continued to form the tongue and groove portions 18, 19 which engage the groove and tongue portions 7 and 9 of the web member.

The tread member is adapted to engage the web member in interlocking relationship by means of the tongue and groove sections above described, and the separate sections are held in their optimum cooperative relationship by any suitable means, such as the bolt and nut construction, now to be described. The tread is provided with a threaded recess 45 20, adapted to receive a threaded bolt 21 passing through aperture 22 in the tread. This threaded aperture is positioned in a lug 22^a of any suitable configuration, which is rolled into the tread member during its fabrication.

As shown, this lug is generally rectangular in shape, although it will be understood that any desired shape may be imparted thereto without departing from the scope of this invention. The tread lug is adapted to fit in locking relationship in the recess 22^b of the web member, as will be seen by inspection of Fig. 3. This recess may be rolled in the web member, or may be machined out, as desired. The cooperative action of the lug and the recess into which it is fitted insures a locking of the tread on to the web in such a manner as to prevent any longitudinal displacement of the tread during service, and in combination with the locking means now to be described, provides positive means for over-

coming lateral, vertical and longitudinal movement of the tread, the combination of elements being simple, effective, and very economical, both in cost of fabrication, as well as in ease of assembly. The bolt is 70 preferably provided with a hexagonal head 23 to facilitate its fastening and removal, although it will be understood that any other suitable configuration may be used. Interposed between the head of the bolt and section 8 of the web is a lock washer 23', adapted to retain the bolt in position and prevent its jarring loose due to vibration stresses when in use. The bolt is preferably inserted from the outside of the rail assembly, thereby 80 securing the full advantage of the retention of the tread member in position upon the web member due to the thrust of the wheel flanges of the railroad cars against surface 14 of the tread.

While the bolt has been shown with its head projecting beyond the outer face of the completed rail, it will of course be understood that the rail may be suitably recessed to receive the bolt head, and that such recessed construction is comprehended in the novel combination of elements of this invention.

The thrust exerted against face 14 of the tread member tends to drive the tongue and groove sections 18 and 19 into locking engagement with the groove and tongue 7 and 9 of the web, and the two rail members are held in this position by the bolt construction above described. It will thus readily be appreciated that the bolt 21 is not required to undergo any appreciable tensile stress while in use other than that normally incident to lateral vibration of the whole rail structure, which in turn is essentially a function of the solidity of the embedment of the rail in or on its supports.

In this connection, the solid steel web provides a perfectly uniform surface for the tread member and minimizes the deteriorative effects of the ordinary tie supports, 110 which are not at all uniform, even in the best maintained roads. That this is true is evidenced by the present day practice of some large railroads of using concrete ties and embedding the rails therein in an effort to provide a maximum amount of stability for the rails.

A further highly advantageous feature of the present invention resides in the fact that by staggering the tread members with respect to the web members, there is provided a continuous metallic bearing surface for the tread members which, in addition to minimizing vibration stresses, as noted above, substantially eliminates another very potent cause of rail destruction, namely, that of the wearing down or attrition of the rail ends due to the pounding of the wheels when passing over the rail joints.

Referring now to Figs. 5 and 6 it will be

noted that the web members have ends, designated generally by the numerals 24, 25, and that the tread members have ends which are designated generally by the numerals 26, 27. By positioning the tread members on the web members so that the ends 26, 27 substantially overlap ends 24, 25 of the web or base members, the first-named end portions of the treads are supported in good mechanical position on a continuous steel surface which affords a maximum of smoothness, and the ends 24, 25 of the supporting webs are overlaid by a continuous stretch of metal whereby both the tread ends and the web ends are given ample support and are no longer subject to the attrition of pounding car wheels, as is usual in ordinary practice.

As has been intimated hereinbefore, the surfaces of the treads of rails used on sharp curves are subject to heavy wear, whereby the rails have to be renewed at very frequent intervals, involving enormous costs both for material, as well as for labor for maintenance. As shown in Fig. 1, such wear usually occurs at the inside surface of a rail which is subjected to the rolling friction of the car wheel flanges, and on the top of the rail where the tread proper is subjected to hammering from the downwardly exerted weight of the rolling stock when any vertical component is imparted thereto as occurs when any inequality in the track or roadbed is present. This attrition of the tread portion of a rail is clearly indicated in Fig. 1 where the worn surface of a rail is shaded and designated by the numeral 30. The inner boundaries of this area are designated by the numerals 31 and 32 respectively, which correspond to the extent of the wearing forces exerted by the flange and the tire of the wheels respectively. The resultant of these forces is the area 30, above described, and any appreciable increase in the extent of this area renders the use of a rail very dangerous and requires the constant replacement discussed above.

Where desired, this invention comprehends the use of structural materials of different characteristics in the tread and web portions of the rails. For example, the tread member may be rolled from a high manganese martensitic steel, while the base or web portion may be rolled from a cheaper stock, such as any of the well-known nickel- or nickel-chromium steels, or other suitable alloy steels.

It will now be seen that there has been provided an improved combination railroad rail having a replaceable tread, which permits the securing of marked economies in railroad operation by the replacement of the tread of a worn rail instead of the replacement of a complete rail with its consequent interruption to traffic and disruption of supporting ties and roadbed.

65 What is claimed is:

1. A rail construction comprising a base web member, a detachable tread portion abutting and overlying the entire upper surface of the web member, said web member and tread portion having centrally disposed laterally extending, respectively, abutting tapering portions, whereby they are substantially locked against relative vertical movement. 70

2. A rail construction comprising a base web member having a vertically offset portion, and a lateral shoulder on said portion extending inwardly and beyond the central vertical plane of the web, a detachable tread overlying substantially the entire upper surface of and adapted to engage said web throughout said surface and formed with a depression adapted to receive the said shoulder in locking engagement. 75

20 3. A rail construction comprising a base plate section and an integral vertical web having a vertical extension on one side, and a lateral, integral tongue on said extension to form two substantially flat vertically offset and respectively overlapping bearing surfaces of substantially equal width. 80

4. A detachable tread for rails comprising an integral metallic member formed with vertically offset flat bearing surfaces of substantially equal width. 85

25 5. A detachable member for rails comprising a metallic member having a flat top portion and a plurality of vertically and horizontally offset bottom weight bearing surfaces and formed with a curvilinear tapering depression between said surfaces. 100

6. A rail construction comprising a base web member, a detachable tread member, said members being formed with integral, interlocking sections adapted to prevent relative vertical movement, and means integral with one of said members extending into and having locking engagement with the other of said members to prevent relative longitudinal movement. 105

40 7. A rail construction comprising a base web member, a detachable tread member, said members being formed with integral, tapered interlocking sections adapted to prevent relative vertical movement, and detachable means extending into and having locking engagement with each of said members in the zone of interlocking to prevent relative lateral movement. 115

8. A rail construction comprising a base web member, a detachable tread member, said members being formed with integral interlocking sections adapted to prevent relative longitudinal movement. 120

45 9. A rail construction comprising a base web member, a detachable tread member, said members being formed with integral, interlocking sections adapted to prevent relative longitudinal and vertical movement. 125

50 10. A rail construction comprising a base 130

web member, a detachable tread member, said members being formed with integral, interlocking sections adapted to prevent relative longitudinal and vertical movement, and means associated with said members to prevent relative lateral movement thereof.

11. A rail construction comprising a base web member, a detachable tread member, said members being formed with integral, interlocking sections adapted to prevent relative longitudinal and vertical movement, and detachable means associated with said members to prevent relative lateral movement thereof.

15. In witness whereof I affix my signature.
